(57) **CLAIM**

The ornamental design for a flexible RFID housing, as shown and described.

DESCRIPTION

FIG. 1 is a perspective view of a flexible RFID housing shown with an RFID chip and a tag shown in dashed lines and exploded therefrom;

FIG. 2 is an assembled view of the flexible RFID housing, the RFID chip and the tag as shown in FIG. 1;

FIG. 3 is a perspective view of the flexible RFID housing tag showing our new design;

FIG. 4 is a top view thereof;

FIG. 5 is a right side view thereof;

FIG. 6 is a front view thereof;

FIG. 7 is a left side view thereof;

FIG. 8 is a bottom view thereof; and,

FIG. 9 is a rear view thereof.

The broken lines in FIGS. 1 and 2 show environment only and form no part of the claimed design. The broken lines in FIGS. 3 and 6 indicate portions of the housing which form no part of the claimed design.
